Inventor:
Leonard V. Middlesworth,
By Rippy Kingland,
His Attorney.

UNITED STATES PATENT OFFICE.

LEONARD V. MIDDLESWORTH, OF ST. LOUIS, MISSOURI.

METAL JOINT.

Application filed April 18, 1925. Serial No. 24,163.

This invention relates to metal joints, and an object thereof is to provide an improved joint in which the crossed metal bars are interlocked by opposite flaring portions of one bar engaging in opposite flaring recesses in the other bar.

Another object of the invention is to provide an improved joint for holding crossed metal bars in rigid connection, comprising 10 a slot in one bar having opposite flaring portions at its inner end, and means for forcing flaring portions of the second bar into the flaring portions of said slot when said two bars are pressed into proper relationship.

Other objects will appear from the following description, reference being made to the drawing in which—

Fig. 1 is a view in elevation showing my 20 improved joint.

Fig. 2 is a sectional view on the line 2—2 of Fig. 1.

Fig. 3 is a view showing the bar with the flaring slot.

Fig. 4 is a similar view of the other bar.

Fig. 5 is a cross sectional view on the line 5—5 of Fig. 2.

Fig. 6 is a sectional view on the line 6—6 of Fig. 4.

Each of the bars shown comprises a web 25 1 and a bead 2 at one edge of the web.

One of the bars is provided with a slot 3 extending through the bead 2 and into the web 1. The inner or bottom wall of the slot 3 is in the form of a wedge 4, and the inner 35 end of said slot 3 comprises opposite flaring portions 5. The bead 2 at each side of the slot 3 is provided with miter recesses 6 to fit closely with corresponding miter recesses 7 in the bead 2 of the other bar.

The web 1 of the other bar is provided

with a slot 8 to receive the web 1 of the bar containing the slot 3, and the bottom wall of said slot 8 is shaped to conform to the shape of the wedge 4.

The joint is formed by crossing the bars as shown in Figs. 1 and 2, and applying pressure thereto to force the bars to a relationship in which their edges are in the same plane and to cause the wedge 4 to force the 45 contacting portions of the bar containing the slot 8 to spread apart and fill the flaring portions 5 of the slot 3, as will be readily understood by reference to Fig. 2. This provides a very strong joint in which a locking 50 device is provided at each side of one of the bars, making it impossible for the bars to be separated.

From the foregoing it will be seen that my improved joint obtains all of its intended 60 objects and purposes in a highly efficient and satisfactory manner, and may be varied somewhat without departing from the nature and principle of the invention.

What I claim and desire to secure by Letters Patent is:—

1. In a joint of the character described, the combination of two crossed bars one of which has a slot therein provided with opposite flaring portions at its inner end, and the other of which fills said slot and has portions flaring oppositely and filling the flaring portions of said slot.

2. In a joint of the character described, the combination of two crossed bars, one of which has a slot therein the bottom wall of which is wedge-shaped and which has opposite flaring portions at the inner end of said slot at opposite sides of said wedge-shaped wall, and the other of which fills said slot 75 and said flaring portions.

LEONARD V. MIDDLESWORTH.
